Mark S. Ordway

ATTORNEY

UNITED STATES PATENT OFFICE.

AUGUST KREMP, OF BADEN-BADEN, GERMANY, ASSIGNOR OF ONE-HALF TO WILLIAM NUSS.

BUILDING STONE.

Application filed November 6, 1923. Serial No. 673,184.

To all whom it may concern:

Be it known that I, AUGUST KREMP, a citizen of Germany, residing at Baden-Baden, have invented certain new and useful

5 Improvements in Building Stones, of which the following is a specification.

The present invention relates to masonry and has for its object to provide building stones or blocks, which will save building 10 material, reduce the time of laying the stones and facilitate the handling thereof.

My invention is illustrated in the accompanying drawing in which similar reference characters denote corresponding parts and 15 in which Fig. 1 is a top plan view of my building stone; Fig. 2 an end view thereof; Figs. 3 and 4 perspective views thereof; Fig. 5 a cross section of a part of a wall built from my new stones; Fig. 6 a top plan 20 view of a new binding stone; Fig. 7 an end view thereof; Figs. 8 and 9 perspective views thereof; Fig. 10 a top plan view of a part of a wall made up of stones shown in Figs. 1-5 and the binding stones shown 25 in Figs. 6-9; Fig. 11 a cross section of said wall and Fig. 12 a similar view showing two superposed rows of such building stones.

The main stone A comprises a top a, one 30 side wall b, two outer or end ribs or slats c and two inner or intermediate ribs or slats d. These ribs are all of uniform thickness and project at right angles to the top and side wall and are made flaring as at c' and d' toward their bottom, so that their outer 35 side edges project laterally in an incline from underneath the top a. The lower edges of the wall of said ribs serve as bases for the blocks. The space between the two central or intermediate ribs is substantially 40 equal to the double thickness of a rib. The block or stone thus produced is hollow and open at its bottom and at one of its sides.

When constructing a wall, the stones are 45 placed in parallel rows with the open sides b' of the stones of the opposite rows facing in a displaced position one another, so that the adjoining end ribs c of adjacent stones of one row are opposite and project into the space between the intermediate ribs d of a stone in the opposite stone row whereby the

opposite rows of stones become interlocked with one another. The stones of the two rows are arranged contiguously as at e (Fig. 5).

For a thicker wall, I use in addition to the 55 two rows of stones A a binding stone B. The latter, like the main stone A comprises a top f, a longitudinally extending vertical central wall g, end ribs i and intermediate ribs j. These ribs i and j in thickness are 60 uniform with one another and substantially equal to the thickness of a rib of the stone A and extend at each side of the central wall g also at right angles thereto and to said top and their outer side edges i' and j' are flaring like those of the ribs e, d.

In use, the main stones are placed in parallel rows and in alignment with and facing one another with their open sides b', but displaced transversely a distance equal to the 70 width thereof or that of a binding stone. The binding stones are inserted between the opposite main stones A and placed endwise in such a position relative to the main stones A that the adjoining end ribs of each two 75 adjacent binding stones B engage the space between the central ribs of the two rows of main stones A and the two end ribs of two adjacent main stones A of each row engage the space between the central ribs 80 of a binding stone B (Figs. 10, 11). In this position, the different sets of stones are cemented together.

Owing to the fact that the vertical crevices between the adjacent stones are not continuous and the fact that the mortar, when the stones are pressed into position, is forced upwardly along the wall and ribs sealing the horizontal crevices, the passage of air 85 through the wall is rendered impossible.

The trapezoid-shaped ribs not only insure the stability of the stones and serve as reinforcements, but also effectively distribute the load, since every upper main stone transmits the load to two lower stones and 90 every upper binding stone to three lower stones (Fig. 12).

The stones should preferably be so dimensioned that in every direction it is a multiple of the standard size of an ordinary brick. 100

This enables the use of said stones between bricks and the filling out of empty corner spaces.

The most important advantages of these stones are the economy in material and saving of time and labor in masonry. Even an untrained laborer after a little instruction can lay these stones with perfect safety.

10. What I claim is:—

1. A building stone or block comprising a top one vertical wall and ribs extending transversely to said top and vertical wall, the lower edges of said wall and ribs serving as base for said stone.

2. A building stone or block comprising a top, a vertical wall and ribs extending transversely to said top and vertical wall and having downwardly flaring side edges, the lower edges of said wall and ribs being even with one another and serving as base for said stone.

3. A building stone or block comprising a top, a vertical wall and ribs extending transversely to said top and vertical wall, there being one of said ribs at each end and intermediate ribs, the lower edges of said wall and ribs being even with one another and serving as base for said stone.

25. 4. A building stone or block comprising a flat top, vertical wall and trapezoid-shaped ribs arranged transversely at right angles to said top and wall, the lower edges of said wall and ribs serving as base for said stone.

30. 5. A binding stone or block comprising a flat top, a vertical longitudinally extending central wall, trapezoid-shaped ribs one at each end and a pair of intermediate ribs in the center of said stone, said ribs projecting

at right angles to said top and wall and extending at each side of the latter, the lower edges of said wall and ribs being even with one another and serving as base for said stone.

45

6. A building stone or block comprising a top, a vertical wall and cross ribs of uniform thickness, there being one cross rib at each end, and a pair of central ribs, said central ribs being spaced apart a distance 50 substantially equal to the double thickness of a rib.

7. A building construction comprising courses of parallel rows of building blocks, each having a top, vertical wall and vertical 55 trapezoid-shaped cross ribs, the lower edges of said wall and cross ribs serving as bases for said blocks, in each course the blocks of one row being directed with their open faces to those of the opposite row and displaced 60 relative thereto, so that the trapezoid-shaped adjacent end ribs of one row engage the space between the central trapezoid-shaped ribs of a block in the opposite row.

8. A building construction comprising 65 courses of two parallel outer rows of building blocks, each having a top, vertical face wall and vertical trapezoid-shaped cross ribs and stones or blocks serving as binding blocks, each binding block having a top, 70 central vertical wall and trapezoid-shaped cross ribs, the opposite blocks of the two outer rows being in alignment with one another and the binding blocks being so displaced relative to said outer blocks that the 75 trapezoid-shaped ribs thereof interlock with the blocks of the two outer rows.

In testimony whereof I affix my signature in presence of two witnesses.

AUGUST KREMP.
